UNITED STATES PATENT OFFICE.

JOHN EDWARD THORNTON, OF PHILADELPHIA, PENNSYLVANIA, ASSIGNOR TO FIRE-PROOF FILM COMPANY, A CORPORATION OF MAINE.

PHOTOGRAPHIC DEVELOPING-TANK.

981,035.

Specification of Letters Patent. Patented Jan. 10, 1911.

Application filed June 28, 1909. Serial No. 504,918.

To all whom it may concern:

Be it known that I, JOHN EDWARD THORNTON, a subject of the King of Great Britain, and resident of Philadelphia, in the county of Philadelphia and State of Pennsylvania, have invented certain new and useful Improvements in Photographic Developing-Tanks, of which the following is a specification.

10 This invention relates to photographic developing tanks for holding developing or other chemicals with which photographic plates or films are treated.

In using the so-called "tank-method" of 15 development, it is desirable, or even necessary, to know the temperature of the developing solution contained in the developing tank in order that the operator may accurately determine the length of time the 20 plates or films should be treated to complete the process of development without inspecting them during the progress of the operation. Hitherto it has been the usual practice to note the temperature of the room in 25 which development is carried on, or else to immerse a thermometer in the liquid, and then, after removal of the same, to place the plates or films in the tank and secure the lid thereon. This method is not accurate 30 because the plates or films may alter the temperature of the solution when immersed, and moreover it is not very convenient.

By this invention a thermometer is combined with the photographic developing tank 35 and so fitted or connected thereto that the stem or tube will be outside and the temperature of the developer contained in the tank can be ascertained at any time during the development.

40 This invention will be fully described with reference to the accompanying drawings in which as examples two forms of photographic development tanks are illustrated, it being understood that the invention may be applied to other of the various forms of photographic washing or developing tanks at present well known.

In the drawings:—Figure 1 is a vertical section of one form of tank with the invention applied thereto; Fig. 2 is a vertical sec-

tion of a modified form of attachment for the thermometer; Fig. 3 is a perspective view of another form of tank with the thermometer applied thereto in the manner of Fig. 2.

The photographic developing tank A in Fig. 1 is made with a vertical recess or groove a with holes a^2 at both bottom and top thereof through which a straight thermometer B is inserted, the recess being of 60 such a length that the bulb b' of the thermometer and the upper end of the stem remain within the interior of the tank. The holes a^2 are sealed after the thermometer is inserted.

Another form of photographic developing tank A is shown in Figs. 2 and 3. The tank is constructed with a vertical slit a^3 in one side and the thermometer B is mounted in a support or bracket D with a recess d to receive the thermometer A and a flange around it by which to secure it to the tank. The thermometer passes through holes d' top and bottom, and is inserted into the interior of the tank through the vertical slit. In a 70 metal tank as shown, the flange d^2 is soldered to the side of the tank, but if the tank is made of pot or other material, it may be affixed by a suitable water proof cement. The stem b of the thermometer stands outside the developing tank.

The photographic developing tank A may be of any of the ordinary known forms such as:—a round tube for roll films, a flat rectangular box for film packs, or a square or 85 rectangular box provided with fixed grooves for plates.

The thermometer B may be charged with mercury, colored spirit, or other suitable fluid and the gradations may be inscribed 90 on the glass or stamped on the side of the tank or on a scale attached thereto.

What I claim is:—

1. A photographic developing tank having a depression in its wall providing a 95 straight external recess, and having openings at the ends of said recess through the wall, and a straight thermometer lying in said recess with its ends projecting through said openings into the interior of the tank. 100

2. A photographic developing tank comprising a body provided with an elongated opening in its wall, and a plate of sheet-metal closing said opening and having a depression providing a straight external recess, and openings at the ends of said recess, and a straight thermometer lying in the re-

cess with its ends projecting through said openings into the interior of the tank.

JOHN EDWARD THORNTON.
